Primary Examiner — Rachel A. Voorhies(74) Attorney, Agent, or Firm — Shuttleworth & Ingersoll, PLC; Timothy Klima(57) CLAIM

The ornamental design for a computer screen with an icon, as shown and described.

DESCRIPTION

FIG. 1 shows a front right side perspective view of a computer screen with an icon showing our new design; FIG. 2 is a rear right side perspective view thereof; FIG. 3 is a top view thereof; FIG. 4 is a left side view thereof; FIG. 5 is a front view thereof; FIG. 6 is a right side view thereof; FIG. 7 is a rear view thereof; and, FIG. 8 is a bottom view thereof.

FIGS. 1-8 show multiple views of an icon displayed on a computer screen with an icon. The outermost broken line represents the computer screen with an icon and forms no part of the claimed design.

1 Claim, 8 Drawing Sheets(56)
